DESIGN FOR A HOUSING FOR DETERGING AND UPHOLSTERY CLEANING MACHINES

Francis U. von Schrader, Racine, Wis.

Application August 16, 1937, Serial No. 71,124

Term of patent 14 years

To all whom it may concern:

Be it known that I, Francis U. von Schrader, a citizen of the United States, residing in Racine, in the county of Racine and State of Wisconsin, have invented a new, original, and ornamental Design for a Housing for Deterging and Upholstery Cleaning Machines, of which the following is a specification, reference being had to the accompanying drawing, forming part thereof.

In the drawing:

Figure 1 is a front elevation of the housing for

deterring and upholstery cleaning machines showing my new design, the rear face of which is identical.

Figure 2 is a plan view; and
Figure 3 is an end elevation.

I claim:

The ornamental design for a housing for deterging and upholstery cleaning machines, as shown and described.

FRANCIS U. VON SCHRADER.
